GLASS TUBE CUTTER

Louis A. Pierson, Meriden, Conn.

Application July 10, 1951, Serial No. 235,925

2 Claims. (Cl. 49—52)

1

This invention relates to a glass tube cutter and has for an object to provide an improved device for cutting glass tubes, particularly of the type used in the medical profession such as suture tubes as used in operating rooms and the necks of ampoules all of which are usually hermetically sealed.

A further object of this invention is to provide an improvement on the ampoule neck cutter shown in my prior Patent 2,447,983 of August 24, 1948.

A further object of this invention is to provide an ampoule or glass tube cutter particularly useful in cutting a hermetically sealed glass tube or ampoule neck so that the contents thereof may be made readily accessible and usable without danger of contamination.

Yet a further object of this invention is to provide a cutter instrument tool that may be readily sterilized simultaneously with other medical or surgical tools, thus insuring against the cutter tool carrying any contamination to the contents of the tube or ampoule.

A further object of this invention is to provide a glass tube cutter which may have its cutter element brought into bearing contact with the glass tube and then held in contact therewith at the same unvarying pressure while the tube or ampoule is rotated to thereby abrade a cutting line completely about the tube, thus enabling the tube to be easily and safely broken at such uniformly abraded cutter line.

With the foregoing and other objects in view, this invention comprises the combination, construction and arrangement of parts hereinafter set forth, claimed and disclosed in the accompanying drawings, wherein:

Fig. 1 is a side plan view, partly in section, of the cutter tool of this invention.

Fig. 2 is an exploded view of the cutter jaws of this tool.

Fig. 3 is a fragmentary partly sectional view of the hinging means of the cutter levers, and

Fig. 4 is a fragmentary sectional view through the levers showing the threaded jaw closing shaft.

There is shown at 10 the glass tube cutter tool of this invention. This invention includes cutter carrying lever 11 having an extending boss 12 near one end thereof adapted to be inserted in a correspondingly shaped slotted aperture 13 in an anvil lever 14. A hinge pin 15 anchored through transverse apertures 16 in the anvil lever 14 and extending through an aligned transverse aperture 17 and the boss 12 serves to journal the cutter lever 11 and anvil lever 14 together. The

anvil lever 14 is curved away at 18 between the journal shaft 15 and its adjacent end 20, thus permitting a limited separation of the anvil and cutter jaw ends of the levers, a spring 21 located in countersunk recesses 22 in the levers serving to normally urge the cutter and anvil jaw ends toward such separated position.

The distance that the cutter lever 11 and anvil lever 14 may be separated from each other is 10 adjustably limited by means of a threaded shaft 23 which is pivoted at 24 through a slotted aperture 25 in the jaw lever 14 and extends through a slotted aperture 26 in the anvil lever 11 and is provided with a knurled nut 27. The nut 27 obviously not only serves to adjustably limit the separation of the jaws 11 and 14, but by being tightened on the threaded shaft 23, it abuts against the back of the cutter lever 11 and thus forces the cutter lever 11 toward the anvil lever 14. The jaw ends 28 of anvil lever 14 is provided as shown with a pair of flats 30 and 31 meeting in an angular recess 32, the flats 30 and 31 thus providing anvil surfaces against which a suture tube 33 may be located while being cut open. The 20 cutter lever jaw end 34 is provided with a pair of flats 35 and 36 whose planes meet at an angle complementary to the angle 32 of the recessed jaw end 28. This jaw end 34 is arranged to receive and hold a cutter wheel 37 which is journaled on the bight 38 of a U-shaped axle 40 having its sides 41 arranged to be received in rearwardly extending slots 42 on the opposite sides of the cutter jaw end 34, the bight 38 being arranged to be received in a transverse slot 43 connecting the rearwardly extending slots 42 25 across the projecting jaw flat 35 and 36. A longitudinally extending slot 44 is provided through the flats 35 and 36 for receiving the cutter wheel 37 therein, this slot 44 extending deeper than the transverse slot 43 and being so related in size 30 to the cutter wheel 37 that the outer edge of the cutter wheel 37 would extend beyond the outer edge of the projecting jaw end 34. The sides 41 of the U-shaped axle 40 are preferably somewhat resilient and extend at a slight angle toward each other so that they may be sprung apart to resiliently hold the axle in position in the rearward slots 42 with the cutter 37 in proper position in its longitudinal slot 44. The cutter wheel 37 35 will be made of any suitable material with an edge of substantially diamond hardness, either a commercial diamond or a material of suitable hardness such as tungsten carbide or other material, thus, in effect, providing a rotary diamond edge suitable for cutting or abrading glass.

In operation, tool may be held in one hand with the jaw ends 34 and 28 just far enough apart to permit the suture tube 33 to be placed therebetween and against the anvil jaw. The knurled nut 27 is then tightened abutting against the back of anvil lever 11 until the cutter wheel 37 has been brought against the side of the suture tube 33 to apply just the proper amount of pressure thereon. Then, holding the tube 33 in one hand and the tool 10 in the other hand the tube and the tool are rotated relative to each other to abrade a complete circle about the tube whereupon the tube may readily be broken along the abraded cutter line thus provided thereon without danger of contaminating the contents of the tube or of the ampoule and without danger of cutting one's fingers. The tool 10 is of hard metal, preferable completely chromium plated about the levers knurled nut or other parts where it may be handled and may be sterilized along with other surgical tools, thus preventing the tool from contaminating the suture tube or ampoule neck on which it is being used. The cutter wheel 37 and its axle 40 may be readily removed and replaced should the cutter become dull at any time.

While the device has been shown and the structure described in detail, it is obvious that this invention is not to be considered as being limited to the exact form disclosed, and that changes in detail and construction may be made therein within the scope of what is claimed, without departing from the spirit of this invention.

Having thus set forth and disclosed the nature of this invention, what is claimed is:

1. An ampoule glass tube cutter comprising a pair of levers pivoted together adjacent one end, yieldable means normally urging their other ends apart, one of said other ends comprising a recessed ampoule tube receiving jaw, the other of said ends comprising a projecting cutter holding jaw, a cutter, said projecting jaw being complementary to said recessed jaw, and means for moving said projecting jaw toward said recessed jaw against the action of said yieldable means to press and hold its cutter against the outer surface of an ampoule glass tube inserted into said recessed jaw, said moving means comprising a threaded shaft pivoted to one on said levers intermediate its ends and extending through an aperture in the other lever, and nut means threaded on said shaft to abut the back of said other lever, whereby when the ampoule glass tube has been inserted between said projecting and recessed jaws, said nut may be tightened

40

against its abutting lever back to press and hold said cutter with a steady pressure against the ampoule tube to cut the ampoule tube as it is rotated therewithin.

2. An ampoule glass tube cutter comprising a pair of levers pivoted together adjacent one end, yieldable means normally urging their other ends apart, one of said other ends comprising a recessed ampoule tube receiving jaw, the other of said ends comprising a projecting cutter holding jaw, a cutter comprising a cutter wheel and a resilient U-shaped axle for said cutter wheel having said wheel journaled on its bight, said projecting jaw having a transverse slot thereacross, a rearwardly extending slot extending therefrom in each of the opposite sides of said jaw of a size to snugly receive said U-shaped axle therein, and a longitudinally extending slot extending deeper than the intersecting transverse slot of a size to permit said cutter wheel to rotate therewithin with its outer cutter edge extending beyond projecting jaw, said projecting jaw being complementary to said recessed jaw, and means for moving said projecting jaw toward said recessed jaw against the action of said yieldable means to press and hold its cutter wheel against the outer surface of an ampoule glass tube inserted into said recessed jaw, said moving means comprising a threaded shaft pivoted to one on said levers intermediate its ends and extending through an aperture in the other lever, and nut means threaded on said shaft to abut the back of said other lever, whereby when the ampoule glass tube has been inserted between said projecting and recessed jaws, said nut may be tightened against its abutting lever back to press and hold said cutter with a steady pressure against the ampoule tube to cut the ampoule tube as it is rotated therewithin.
